UNITED STATES PATENT OFFICE.

BENJAMIN M. FRANK, OF NEW YORK, N. Y., ASSIGNOR TO GREENPOINT METALLIC BED CO., INC., OF BROOKLYN, NEW YORK, A CORPORATION OF NEW YORK.

DESIGN FOR AN ORNAMENT FOR BEDSTEAD FRAMES.

Application filed July 7, 1923. Serial No. 6,726. Term of patent 3½ years.

To all whom it may concern:

Be it known that I, BENJAMIN M. FRANK, a citizen of the United States, residing at New York city, in the county and State of New York, have invented a new, original, and ornamental Design for an Ornament for Bedstead Frames, of which the following is a specification, reference being had to the accompanying drawings, forming a part thereof, and in which Fig. 1 is a front elevation and Fig. 2 a side edge view of an ornament for bedstead frames embodying my design.

I claim:

The ornamental design for an ornament for bedstead frames, as shown.

BENJAMIN M. FRANK.
